SEGREGATION OF TERTIARY BASE
OLEFINES

William Engs and Richard Moravec, Berkeley,
Calif., assignors to Shell Development Com-
pany, San Francisco, Calif., a corporation of
Delaware

No Drawing. Application June 1, 1931, Serial
No. 541,526.

28 Claims. (Cl. 260—170)

This invention relates to a process for the seg-
regation of highly reactive olefines from olefinic
mixtures containing more than three carbon
atoms and is more particularly concerned with a
5 continuous cyclic process which effects an econ-
omy in the necessary amount of selective solvent
required to selectively absorb the highly reactive
olefine content.

Prior investigators have utilized olefine-con-
10 taining gases, such as those derived by the pyro-
genetic treatment of peat, coal, oil shales and
like carboniferous natural materials to produce
secondary alcohols but very few have been con-
cerned with the selective removal of highly re-
15 active unsaturates prior to the formation of the
desirable secondary alcohols.

We have discovered that secondary alcohols
can be prepared simply and economically from
20 olefine-containing gases of the type mentioned
heretofore by practicing the selective removal of
highly reactive olefines in a continuous manner
wherein the selective absorbent is continuously
recovered and recycled for further use.

The preferred initial material is substantially
25 stripped of hydrocarbons containing less than
four carbon atoms and suitably fractionated into
fractions containing hydrocarbons of the same
number of carbon atoms. In certain instances,
it will be difficult to remove traces of higher and
30 lower carbon compounds, but their presence is
not detrimental to this process. In certain other
situations, it may be desirable to operate with a
fraction containing a mixture of carbon com-
pounds such as a 4 and 5 carbon compound frac-
35 tion. We prefer to practice our process with a
substantially pure fraction of hydrocarbons of
which each molecule contains the same number
of carbon atoms. In segregating the hydrocar-
bons into suitable fractions, it will be found that
40 it will be practically impossible to separate the
paraffin hydrocarbons from the olefine hydrocar-
bons possessing the same number of carbon atoms
without uneconomical and complicated pro-
cedure. As the paraffin hydrocarbons may be
45 considered as inert compounds in our process,
their presence in their corresponding carbon
compound fraction is not accompanied by any
detrimental effect.

50 The fractions to be treated are thus character-
istically composed of paraffin hydrocarbons, ole-
fines, both iso- and normal, which yield sec-
ondary derivatives (hereinafter designated as sec-
ondary-base olefines), iso-olefines which yield
55 tertiary derivatives (hereinafter designated as

tertiary-base olefines) and traces of diolefines
such as butadiene and isoprene.

For illustrative purposes only, references will
be had to a substantially pure B-B fraction
which represents a mixture of butane and bu-
tene obtained by distillation or condensation or
both. Besides the butane there will be normally
5 present isobutane, butene-1, butene-2 and iso-
butene. Isobutene is characteristic of the ter-
tiary-base olefines as regards their high rates
of reactivity with various reagents. It is prefer-
able to selectively remove the isobutene content
10 prior to the conversion of the secondary-base
olefines to secondary alcohols otherwise the ter-
tiary-base olefine polymerizes, causing local
overheating and thus decreasing the possible ef-
fective yields of secondary alcohols, or incom-
15 plete conversion of the secondary-base olefines
results from the desire to avoid excessive poly-
merization of the tertiary-base olefine.

20 Selective absorbents for tertiary-base olefines
are polybasic acids (of which sulfuric acid or
phosphoric acid are typical). In certain in-
stances it may be desirable to employ monobasic
acids as hydrochloric acid or organic acids as
25 benzene sulfonic acids or the sulfonic acids of
the homologues of benzene.

30 The desired fraction, either in the gaseous or
liquid state—the liquid state promoting in-
creased surface contact—is contacted with the
selective absorbent in any suitable manner with
or without pressure. For example, resort may
35 be had to the agitation of the two agents in a
common vessel or to counter-current flow. It is
desirable when employing a fraction in the gase-
ous state to conduct the process in counter-cur-
rent fashion through a packed tower as this sys-
35 tem lends itself most readily to intimate dis-
tribution of the tertiary-base olefine in the se-
lective absorbent. Care must be taken that the
40 strengths of the selective absorbents are regu-
lated according to the temperature of the proc-
ess and according to the character of the ter-
tiary-base olefine. In practicing our invention,
we preferably employ sulfuric acid containing
45 between 60% and 70% H_2SO_4 , preferably 65%
 H_2SO_4 as it apparently yields the best results
with 4 or 5 carbon fractions and the like. While
the B-B fraction is in intimate contact with
50 the sulfuric acid the temperature is kept below
90° F. The isobutylene dissolves in this concen-
tration of acid while the butene-1 and butene-2
substantially do not, but remain associated with
the butane. The sulfuric acid solution of iso-
55 butylene is mechanically separated from the un-

dissolved fraction in any suitable manner as known to the art. The solution of isobutylene is then heated to an elevated temperature around 180° F. which results in the formation of polymers of isobutylene which are hydrocarbons immiscible with sulfuric acid and therefore easily separated therefrom by any suitable operation known to the art. The polymers may be admixed with hydrocarbon fuel to enhance the 10 anti-knock rating of the latter. The recovered sulfuric acid is cooled to the desired temperature prior to recycling in order to avoid solution of secondary-base olefines. The acid may be cooled prior to the separation of the polymer 15 therefrom. Thus by continuously introducing a selective absorbent and a preferred hydrocarbon fraction in a suitable contact vessel, selectively removing the tertiary-base olefine and continuously recovering and recycling the selective absorbent, we have a closed, complete continuous process which furnishes a hydrocarbon fraction practically devoid of tertiary-base olefines, which yields a desirable anti-knock agent and which requires a minimum of selective absorbent to operate, all tending towards a flexible, easily regulatable process which constitutes 20 an advance in the art relating to the preparation of secondary alcohols.

When diolefines are present in the fraction undergoing treatment, they are selectively absorbed practically simultaneously with the tertiary-base olefines and are removed with the solution of tertiary-base olefines. The selective absorbent which is recovered after separation of the 30 polymers and recycled to the absorption system is a dilute acid liquor which does not contain substantial amounts of alkyl sulfates.

While we have in the foregoing described in some detail the preferred embodiment of our 40 invention and some variants thereof, it will be understood that this is only for the purpose of making the invention more clear and that the invention is not to be regarded as limited to the details of operation described, nor is it dependent upon the soundness or accuracy of the theories which we have advanced as to the reasons for the advantageous results attained. On the other hand, the invention is to be regarded as limited only by the terms of the accompanying 45 50 claims, in which it is our intention to claim all novelty inherent therein as broadly as is possible in view of the prior art.

We claim as our invention:

1. The continuous process for the selective removal of tertiary-base olefines from hydrocarbon mixtures containing the same, comprising contacting the hydrocarbon mixture in the liquid phase with a selective acid absorbent for the tertiary-base olefine, separating the solution of the 55 60 tertiary-base olefine from the undissolved hydrocarbon mixture, polymerizing the dissolved tertiary-base olefine, effecting the separation of the polymer from the selective absorbent and recycling the recovered selective absorbent so that it is contacted with fresh hydrocarbon mixtures containing tertiary-base olefines.

2. The continuous process for the selective removal of tertiary-base olefines from hydrocarbon mixtures containing paraffin and olefine hydrocarbons of the same number of carbon atoms, comprising contacting the hydrocarbon mixture in the liquid phase with a selective acid absorbent for the tertiary-base olefine, separating the solution of the tertiary-base olefine from the undissolved hydrocarbon mixture, polymerizing the dissolved tertiary-base olefine, effecting the separation of the polymer from the acid and recycling the recovered acid so that it is contacted with fresh hydrocarbon mixtures containing tertiary-base olefines.

the dissolved tertiary-base olefine, effecting the separation of the polymer from the selective absorbent and recycling the recovered selective absorbent so that it is contacted with fresh hydrocarbon mixtures containing tertiary-base olefines. 5

3. The continuous process for the selective removal of tertiary-base olefines from a hydrocarbon mixture produced by cracking petroleum oil and containing paraffin and olefine hydrocarbons of the same number of carbon atoms, comprising 10 contacting the hydrocarbon mixture in the liquid phase with a selective acid absorbent for the tertiary-base olefine, separating the solution of the tertiary-base olefine from the undissolved hydrocarbon mixture, polymerizing the dissolved tertiary-base olefine, effecting the separation of the polymer from the selective absorbent and recycling the recovered selective absorbent so that it is contacted with fresh hydrocarbon mixtures containing tertiary-base olefines. 15 20

4. The continuous process for the selective removal of tertiary-base olefines from a hydrocarbon mixture produced by cracking petroleum oil and which consists predominantly of paraffin and olefine hydrocarbons of the same number of carbon atoms, comprising 25 contacting the hydrocarbon mixture in the liquid phase with a selective acid absorbent for the tertiary-base olefine, separating the solution of the tertiary-base olefine from the undissolved hydrocarbon mixture, polymerizing the dissolved tertiary-base olefine, effecting the separation of the polymer from the selective absorbent and recycling the recovered selective absorbent so that it is contacted with fresh hydrocarbon mixtures containing tertiary-base olefines. 30 35

5. The continuous process for the selective removal of isobutylene from a hydrocarbon mixture produced by cracking petroleum oil and which consists predominantly of paraffin and olefine hydrocarbons of four carbon atoms, comprising 40 contacting the hydrocarbon mixture in the liquid phase with a selective acid absorbent for the isobutylene, separating the solution of isobutylene from the undissolved hydrocarbon mixture, polymerizing the dissolved isobutylene, effecting the separation of the polymer from the selective absorbent and recycling the recovered selective absorbent so that it is contacted with fresh hydrocarbon mixtures containing isobutylene. 45 50

6. The continuous process for the selective removal of tertiary-base olefines from hydrocarbon mixtures containing the same, comprising contacting the hydrocarbon mixture with aqueous sulfuric acid between 60 to 70% H_2SO_4 content, 55 separating the solution of the tertiary-base olefine from the undissolved hydrocarbon mixture, polymerizing the dissolved tertiary-base olefine, effecting the separation of the polymer from the acid and recycling the recovered acid so that it is contacted with fresh hydrocarbon mixtures containing tertiary-base olefines. 60

7. The continuous process for the selective removal of tertiary-base olefines from hydrocarbon mixtures containing paraffin and olefine hydrocarbons of the same number of carbon atoms, comprising contacting the hydrocarbon mixture with aqueous sulfuric acid between 60 to 70% H_2SO_4 content, separating the solution of the tertiary-base olefine from the undissolved hydrocarbon mixture, polymerizing the dissolved tertiary-base olefine, effecting the separation of the polymer from the acid and recycling the recovered acid so that it is contacted with fresh hydrocarbon mixtures containing tertiary-base olefines. 65 70 75

with aqueous sulfuric acid between 60 to 70% H₂SO₄ content at a temperature below 90° F., separating the solution of tertiary-base olefine from the undissolved hydrocarbon mixture, heating said solution to an elevated temperature so that polymerization of the dissolved tertiary-base olefine is effected, separating the polymer from the acid and recycling the recovered acid so that it is contacted with fresh hydrocarbon mixtures containing tertiary-base olefines.

19. The continuous process for the selective removal of tertiary-base olefines from a hydrocarbon mixture produced by cracking petroleum oil and which consists predominantly of paraffin and olefine hydrocarbons of the same number of carbon atoms, comprising contacting the hydrocarbon mixture with aqueous sulfuric acid between 60 to 70% H₂SO₄ content at a temperature below 90° F., separating the solution of tertiary-base olefines from the undissolved hydrocarbon mixture, heating said solution to an elevated temperature so that polymerization of the dissolved tertiary-base olefine is effected, separating the polymer from the acid and recycling the recovered acid so that it is contacted with fresh hydrocarbon mixtures containing tertiary-base olefines.

20. The continuous process for the selective removal of isobutylene from a hydrocarbon mixture produced by cracking petroleum oil and which consists predominantly of paraffin and olefine hydrocarbons of four carbon atoms, comprising contacting the hydrocarbon mixture with aqueous sulfuric acid between 60 to 70% H₂SO₄ content at a temperature below 90° F., separating the solution of isobutylene from the undissolved hydrocarbon mixture, heating said solution to an elevated temperature so that polymerization of the dissolved isobutylene is effected, separating the polymer from the acid and recycling the recovered acid so that it is contacted with fresh hydrocarbon mixtures containing isobutylene.

21. The process of reacting an olefine mixture in the liquid phase with diluted sulfuric acid via absorption and subsequent heating whereby substantially only the tertiary olefine content forms polymers, separating from the acid liquor a substantial proportion of the polymers, and then bringing the separated acid liquor into contact with an additional quantity of olefine mixture.

22. The process of reacting an olefine mixture in the liquid phase with sulfuric acid of concentration below 70 per cent via absorption and subsequent heating whereby substantially only the tertiary olefine content forms polymers, separating from the acid liquor a substantial proportion of the resulting polymers and then bringing the separated acid liquor into contact with an additional quantity of olefine mixture.

23. Process of producing hydrocarbons boiling within the gasoline range from a mixture of hydrocarbons containing normal and iso olefines derived from the pyrolysis of mineral oil, which comprises treating said mixture in the liquid phase with aqueous sulphuric acid, under conditions of acid concentration and temperature adapted to selectively form the absorption product of the tertiary iso olefines present in said mixture with the formation of an acid liquor con-

taining said absorption products, removing said acid liquor, heating the same, and separating the oily polymers thereby produced.

24. Process of producing hydrocarbons boiling within the gasoline range from a mixture of hydrocarbons containing normal and isoolefines derived from the cracking of mineral oil, which comprises treating said mixture with aqueous sulphuric acid of from 60 to 70% acid concentration while maintaining a temperature at which there is selectively formed the absorption products of the tertiary isoolefines present in said mixture, thereby forming an acid liquor containing said absorption products, removing said acid liquor, heating the same, and separating the oily polymers thereby produced.

25. Process of producing hydrocarbons boiling within the gasoline range from a mixture of hydrocarbons containing normal and isoolefines derived from the cracking of petroleum oil, which comprises treating said mixture with aqueous sulphuric acid of from 60 to 70% acid concentration at a temperature of from 0 to 25° C. thereby selectively forming the absorption products of the tertiary isoolefines present in said mixture with the formation of an acid liquor containing said absorption products, removing said acid liquor, heating the same, and separating the oily polymers thereby produced.

26. Process of producing hydrocarbons boiling within the gasoline range from a mixture of hydrocarbons containing normal and isobutylene derived from the pyrolysis of mineral oil, which comprises treating said mixture in the liquid phase with aqueous sulphuric acid, under conditions of acid concentration and temperature adapted to selectively form the absorption product of the isobutylene present in said mixture with the formation of an acid liquor containing said absorption product, removing said acid liquor, heating the same, and separating the oily polymers thereby produced.

27. Process of producing hydrocarbons boiling within the gasoline range from a mixture of hydrocarbons containing normal and isobutylene derived from the pyrolysis of mineral oil, which comprises treating said mixture with aqueous sulphuric acid of from 60 to 70% acid concentration while maintaining a temperature at which there is selectively formed the absorption product of the isobutylene present in said mixture, thereby forming an acid liquor containing said absorption product, removing said acid liquor, heating the same, and separating the oily polymers thereby produced.

28. Process of producing hydrocarbons boiling within the gasoline range from a mixture of hydrocarbons containing normal and isobutylene derived from the pyrolysis of mineral oil, which comprises treating said mixture with aqueous sulphuric acid of from 60 to 70% acid concentration at a temperature of from 0 to 25° C., thereby selectively forming the absorption product of the isobutylene present in said mixture with the formation of an acid liquor containing said absorption product, removing said acid liquor, heating the same, and separating the oily polymers thereby produced.
